UNITED STATES PATENT OFFICE.

CHARLES W. PROCTOR, OF LAKE FOREST, ILLINOIS.

OIL-CAN.

SPECIFICATION forming part of Letters Patent No. 558,207, dated April 14, 1896.

Application filed December 9, 1895. Serial No. 571,602. (No model.)

To all whom it may concern:-

Be it known that I, CHARLES W. PROCTOR, a citizen of the United States, residing at Lake Forest, in the county of Lake and State of Illinois, have invented certain new and useful Improvements in Oil-Cans, of which the following is a specification, reference being had to the accompanying drawings, in which—

Figure 1 is a central vertical section through an oil-can embodying my improvements, and Fig. 2 is a detail illustrating a modification.

This invention relates to cans containing oil from which from time to time a supply is to be drawn for filling lamps, oil-stoves, or other devices, and has for its object to equip such a can with devices whereby the contents can be forced out through a suitable discharge-tube by means of atmospheric pressure and the flow instantly stopped, when desired, by shutting off such pressure. I attain this object by the construction of devices, as shown and as hereinafter fully described.

That which I regard as new will be set forth in the claims.

25 In the drawings, *a* indicates an oil-can, which may be of any suitable size and construction.

b indicates an ordinary cap screwed upon the usual nozzle on the top of the can.

30 *c* indicates a short tube passing through the cap *b* and soldered or otherwise firmly affixed to said cap. This tube is closed at its lower end, and near such end, in the wall of the tube, are a number of small openings *d*.

35 *e* is another tube of sufficiently less diameter than the tube *c* to enable it to fit within and be movable in said tube *c*. This tube *e* is open at both its ends.

40 *f* is a coiled spring encircling said tubes *c* and *e* and having its ends bearing against shoulders *g g'*, secured, respectively, to the tubes *c* and *e*.

45 *h* is a discharge-pipe, the upper end of which is curved to better discharge into a vessel and the lower end is extended to near the bottom of the can. This tube *h* also passes through the cap *b*, and, like the tube *c*, is firmly soldered or otherwise secured to said cap. The joints formed by the tubes passing 50 through the cap are to be made air-tight.

For strengthening purposes the two tubes

c and *h* are soldered or otherwise secured together, as at *i*.

The operation is as follows: The parts being in the position shown in Fig. 1 and it being desired to discharge some of the contents into a lamp, an oil-stove, or some other vessel, air is forced into the can, preferably by blowing with the mouth into the upper end of the tube *e*. The air passes through the tubes *e* and *c* and through the openings *d* into the can. When a sufficient amount of air has thus been forced into the can to produce the required pressure, oil will flow from the discharge-tube *h*. As soon as the required amount of pressure is had to start the flow of oil through the tube *h* the blowing of air through the tubes *e* and *c* is to be discontinued, and simultaneously therewith the tube *e* is to be forced down by the operator 55 against a compressible washer located in the bottom of the tube *c*. This will bring the tube *e* opposite all of the openings *d* and thus prevent the escape of air from the can. The tube *e* is to be held down opposite the openings *d* 60 until the desired amount of oil has been drawn off. The tube *e* is then to be released by the operator, when, through the action of the coiled spring *f*, such tube *e* will be returned to its normal position and the air in 65 the can allowed to escape by means of the openings *d* and tubes *c* and *e*. The pressure being thus removed from the oil the flow through the tube *h* will cease, and by the suction created the tube *h* will be given a 70 siphonic action and waste of oil prevented.

In the modification illustrated the tube *c* is not perforated and is not closed at its lower end. In this construction the inner tube *e* is adapted to be pushed past the end of the outer 75 tube *c* and against a cork or other suitable stop *l*, secured to the discharge-tube *h*. When so pressed down, it will effectually prevent the escape of air from the can, and when the downward pressure on the tube *e* is released 80 air from the can will escape through the open lower end of such tube, thus shutting off the escape of oil through the discharge-tube *h*, as before described.

I am aware that it is not new with me to 85 provide an oil-can with devices for forcing air into the can in order to effect a discharge

of the oil in the can, which devices are provided with means for permitting the rapid escape of air from the can when it is desired to shut off the flow; but many of the former devices have been objectionable, either on account of comparatively expensive valves or on account of the use of elastic tubing, which is soon injuriously affected by the use to which it is put. By my construction a very effective device is provided at very small cost, and one that can be readily removed from a can to permit the can to be filled or cleaned. When removed from the can, there are no openings left other than the usual filling-opening, which can be closed with the ordinary screw-cap.

That which I claim as my invention, and desire to secure by Letters Patent, is—

1. The combination with an oil-can provided with a discharge-tube, of a stationary tube secured to said can one end of which projects within the can, a longitudinally-movable tube arranged within said stationary

tube, means for preventing the escape of air from the can when the longitudinally-movable tube is forced down, and means for returning to and normally holding said longitudinally-movable tube in its elevated or normal position, substantially as described. 25

2. The combination with an oil-can provided with a discharge-tube, of a stationary tube secured to said can and projecting thereinto, a stop *l* secured to the discharge-tube below the stationary tube, a longitudinally-movable tube arranged within the stationary tube and adapted when forced down to contact with the stop *l* and prevent the escape of air from the can, and means for returning said longitudinally-movable tube to its elevated or normal position, substantially as described. 30 35
